United States Patent Office

Des. 215,182
Patented Sept. 9, 1969

215,182

SPOON OR SIMILAR ARTICLE

Raymond T. Cleeland, Freehold, N.J., assignor to American Home Products Corporation, New York, N.Y., a corporation of Delaware

Filed Oct. 30, 1968, Ser. No. 14,239

Term of patent 14 years

Int. Cl. D7—03

U.S. Cl. D54—12

FIG. 1

FIG. 2

FIG. 3

FIG. 4

FIG. 1 is a front elevational view of a spoon or similar article showing my new design.

FIG. 2 is a side elevational view thereof.

FIG. 3 is a back elevational view thereof.

FIG. 4 is an enlarged section on line 4—4 of FIG. 1.

The drawing is shaded to indicate contrast.

I claim:

The ornamental design for a spoon or similar article, substantially as shown and described.
